COMBINED NIGHT STICK, FLASHLIGHT, AND AUDIBLE ALARM

Rubin Duffy Lewis, Scarsdale, N.Y.

Application July 26, 1957, Serial No. 674,526

11 Claims. (Cl. 340—384)

This invention relates to protective devices of the 15 type adapted to be carried by people for the purpose of enabling them to protect themselves in the event of threat of bodily harm, burglary and the like.

An object of the invention is to provide a novel and improved protective device of the above type, which combines in a single unit a night stick or club, a flash-light and an audible alarm.

Another object of the invention is to provide an improved protective device as above characterized, wherein the audible alarm will be automatically energized or set off if the device should be jarred or jolted, as by being dropped and striking the pavement, or by being suddenly halted as when moving rapidly and striking an impediment.

A still further object of the invention is to provide an improved protective device as characterized, wherein appreciable and sufficient weight is obtained from the various components utilized in providing the flash-light and signal means in conjunction with a hollow metallic casing therefor of somewhat increased thickness, to enable the device to satisfactorily function as a club or stick.

A feature of the invention resides in the provision of an improved protective device as above set forth, wherein the overall shape and configuration is not greatly different from that of an ordinary round and stout night stick and club.

Another feature of the invention resides in the provision of an improved device for personal protection incorporating the above construction wherein easily operable manual switch means are disposed to enable either the flash light or the audible signal means or both to be readily activated when desired.

Yet another feature of the invention resides in the provision of a novel and improved protective device adapted to be carried by a person, which device has all of the above advantages and functions and is nevertheless simple in its construction and economical to fabricate.

Other features and advantages will hereinafter appear.

In the drawings accompanying this specification, similar characters of reference indicate corresponding parts wherever possible in the several views, in which:

Figure 1 is an axial sectional view of a protective device made in accordance with the invention.

Fig. 2 is a transverse sectional view taken on line 2—2 of Fig. 1.

Fig. 3 is a transverse sectional view taken on line 3—3 of Fig. 1.

Fig. 4 is a transverse sectional view taken on line 4—4 of Fig. 1.

As shown, the improved protective device of the present invention comprises an elongate tubular casing 10 which may be advantageously formed of metal tubing or pipe having a relatively thick wall to provide the casing with a certain amount of desirable weight whereby it is usable substantially as a night stick or club.

2

Disposed at one end 11 of the casing 10 I provide an audible signal means indicated generally by the numeral 12, and at the other casing end 13 I provide electric flash light means indicated generally by the numeral 14. Intermediate the ends 11 and 13 of the casing and the signal and light means 12 and 14 there is disposed a battery power means which may be advantageously in the form of a plurality of flash light cells 15 positioned to effect a series connection between them.

10 The audible signal means 12, flash light means 14 and batteries 15 provide advantageously an additional weight to the casing 10, to render the same more effective when it is being used as a club, as will be readily understood.

Referring to Figs. 1 and 2, the audible signal means 12 comprises a diaphragm 17 disposed across the interior of the casing 10, said diaphragm being adapted to vibrate so as to constitute, with the casing end 11, a horn. The diaphragm 17 is preferably of magnetic material, by which it is attracted by a magnet coil 18 having a core 19 extending in close proximity to the inner face of the diaphragm.

As shown in Fig. 1, the magnet coil 18 may be mounted in a metal cup 20, which when formed of magnetic material will constitute in large measure a return magnetic 25 circuit for the coil 18. The cup 20 is shown as fitting normally within the casing 10, and in the event that the casing should also be constituted of magnetic material it would further act as a part of a return magnetic circuit for the magnet.

30 The end 11 of the casing 10 has a perforated grill plate or disc 22 which is secured in a sleeve 23 snugly fitted in the casing 10 and at its inner end having an in-turned flange for positioning an annular insulating ring 25 in which the diaphragm 17 is carried. An externally threaded ring 26 secures the insulating ring 25 in place, against the internal flange of the sleeve 23.

Attached to the diaphragm 17 is a breaker arm 28 to which one end 29 of the coil 18 is attached, said breaker arm extending through an opening 30 in the cup 20 and being engageable with a contact 31 carried by a stepped contact cup 32 mounted within an insulated sleeve 33 snugly fitted in the casing 10.

40 Attraction of the diaphragm 17 by the core 19 will effect a flexing of the diaphragm and a separation of the breaker arm 28 from the contact 31, and such action is utilized to continually interrupt the circuit through the magnet coil 18 in the well-known manner of a buzzer, to effect continuous vibration of the diaphragm 17. This will, in the manner of a horn, provide a loud audible signal, the sound emanating from the protective end grill 22.

45 Between the audible signal 12 and the batteries 15 I provide a manually operable switch means comprising in part the stepped contact cup 32 and a second contact cup 35, the latter being also carried within the insulating sleeve 33 and being adapted to engage a center terminal post 36 of the adjacent battery 15. The insulating sleeve 33 has slots or notches 38 and 39, through which a switch contact spring 40 may extend, such spring being carried on a knob or button 41 and being adapted to bridge the contact cups 32 and 35 as shown in Fig. 1 to effect a closure of the circuit through the signal means 12. The spring 40 and button 41 are movable to the left from the position shown, to disconnect the cups 32 and 35 from each other, thereby to open the circuit through the alarm device 12. The button 41 may be carried in a formed sheet metal slide member 42, which may be attached to the casing 10 by any suitable means, that shown being in the form of rivets. Completion of the circuit for the signal 12 is effected by connecting the remaining wire 44 from the coil 18 to the metal cup 20

which is grounded on the casing 10. It will be understood, as is also hereinafter disclosed, that the remaining terminal of the battery power means 15 is also grounded on the casing 10 at all times. By the above construction, the person carrying the protective device may whenever desired activate the signal 12 by shifting the button 41 into the position of Fig. 1, and may shut off the signal by returning the button to its open-circuit position.

In accordance with the present invention I also provide an automatic switch means for activating the audible signal 12, said automatic being responsive to any appreciable jarring or jolting of the casing 10. This automatic switch means is shunted across the manually operable switch means, and comprises a metal weight 46 carried by a metal coil spring 47 which is rigidly secured to the bottom of the contact cup 35. The weight 46 has an eye or loop 48 engageable with an insulating hook 49 which is secured to the bottom of the cup 32 and is constituted of an insulating material such as nylon plastic or the like. Normally, when the weight 46 is hooked as shown in Fig. 1, the automatic switch is open-circuit. However, if the casing 10 should be jarred or jolted it would disengage the weight 46 from the hook 49 and the said weight would then rest against a ridge or shoulder 50 of the cup 32, by virtue of the spring 47 yielding under the force of the weight, thereupon electrically connecting the contact cups 32 and 35 and closing the circuit through the alarm device 12. The alarm will now be given, and may be shut off by standing the protective device on its end 11, in an upright position. Since such positioning of the protective device is extremely unlikely during a scuffle, or when the device falls to the ground, it is virtually impossible to prevent the alarm from being sounded once the weight 46 has become disengaged from the hook 49.

Also, in accordance with the present invention I provide novel means for energizing the flash light portion 14 of the protective device. This means comprises a metal tube or sleeve member 53 which surrounds the casing 10 and is insulated therefrom by an interposed insulating sleeve 54. On the tubular member 53 I provide a formed metal slide member 56 carrying a switch button 57 which has a connecting arm 58 extending through slots 59, 60 and 61 in the sleeves 53 and 54, and the casing 10 respectively. The contact arm 58 is adapted to engage a contact button 63 carried by the insulating sleeve 33 and the contact cup 35, such button being electrically connected to said cup. By this organization, shifting of the button 57 from left to right as viewed in Fig. 1 will cause the arm 58 to engage the contact 63, thereby applying an energizing potential to the outer metal tube or sleeve 53.

At the end 13 of the casing 10 I provide a removable cap in the form of an annulus or ring 65 having a lens disc 66 and a reflector 67 in which latter a bulb 68 is carried. The ring 65 has bayonet slots 70 cooperable with bayonet pins 71 of the casing end 13 whereby the cap may be readily applied to or removed from the casing. The cap also comprises a metal cup 73 secured to the ring 65 and having a coil spring 74 engageable with the bottom terminal surface of the end battery cell 15 to effect a grounding connection from the battery power means to the casing 10.

In the cup 73 there is provided an insulating strip 76 carrying a contact member 77 engaged with the tip contact of the bulb 68, said member extending through a slot 78 in the cup 73 and engaging a contact stud 80 which is carried by the outer tube 53 and is insulated from the casing 10 by a bushing 81. In this manner a circuit is effected from the tube 53 through the lamp 68 to the ground or casing 10, inasmuch as the reflector 67 is of metal and engages not only the shell of the lamp 68 but also the cap ring 65.

It will be readily understood that actuation of the

switch button 57 may now effect energizing of the lamp 68 from the batteries 15. It will be seen that batteries 15 may be readily removed and replaced by merely removing the cap ring 65 and flash light assemblage attached thereto, as made possible by the bayonet slot and pin connection between the ring 65 and the casing 10.

It will be further understood that, as effected by the above construction, I have provided a novel and improved protective device constituted to function as a 10 night stick or club, said device having incorporated therein a flash light means and an electric, audible alarm means and further including an automatic switching arrangement by which a loud sound or signal will be given in the event that the device is suddenly jarred or jolted. 15 The construction is relatively simple and utilizes few components which may be economically fabricated and assembled.

Variations and modifications may be made within the scope of the claims, and portions of the improvements 20 may be used without others.

I claim:

1. A device of the character described, comprising in combination an elongate tubular casing in the form of a club adapted to be held in the hand, said casing having 25 relatively thick and heavy side walls; battery power means disposed in said casing; electric flash light means in said casing; audible electric signal means in said casing; manually operable switch means on the casing, for energizing said light means or said signal means at will from 30 the power means by a person holding the casing in the hand; an automatic shunting switch means connected to said manually operable switch means, for permanently closing the circuit through the audible signal means in response to the said casing suffering a jolt, said shunting switch means in the absence of the said jolt being 35 normally inoperative to close the circuit regardless of the position in which the casing is placed, and said switch means including a conducting, circuit-closing element and a mechanical supporting structure normally holding said 40 element in an open-circuit position, said structure being deformable in response to the casing being jolted, to release the element for closing the said circuit.

2. The invention as defined in claim 1 in which the audible signal means is disposed at one end of the casing, 45 in which there is an open sound cavity at said one end, in which the light means is disposed at the other end of the casing, and in which the battery power means is disposed intermediate the ends of the casing, between the said signal means and light means.

3. The invention as defined in claim 2 in which the manually operable switch means comprises a pair of electric switches having manually operable members respectively, disposed outside of the casing, one operable member being located adjacent and controlling the signal 55 means and the other operable member being located closer to the said light means than the said one operable member and controlling said light means, the said relative positions of the operable members being thus indicative of means which they control.

4. The invention as defined in claim 3 in which the casing comprises an inner metal tube connected to one terminal of the power means, and comprises a second and outer metal tube enclosing and insulated from the first-mentioned tube, said second metal tube being connected to one 60 of said electric switches and thereby adapted for connection to the other terminal of the power means, said battery power means being carried in and being separate from said inner metal tube.

5. The invention as defined in claim 4 in which the 65 flash-light means comprises a bulb and reflector therefor, in which there is a cap attached to an end of the casing, mounting said bulb and reflector, and in which there is an insulated contact carried by said cap, connected with the said outer tube of the casing when the cap is attached 70 to the latter.

6. The invention as defined in claim 5 in which there is a bayonet pin and slot connection between the said cap and casing.

7. The invention as defined in claim 2 in which the manual switch means comprises a pair of rings disposed in the casing between the signal means and the power means, comprises means insulatedly mounting said rings, and a manually operable bridging member adapted to electrically connect the rings with each other and disconnect the rings from each other according to its position.

8. The invention as defined in claim 2 in which the manual switch means is disposed in the casing between the signal means and the power means.

9. The invention as defined in claim 1 in which the audible signal means comprises a diaphragm extending across the interior of the casing at one end, and electric means for vibrating said diaphragm at a rapid rate said diaphragm having its peripheral portions secured to the casing.

10. The invention as defined in claim 1 in which the audible signal means comprises a diaphragm disposed in the casing and electro-magnetic means for vibrating said diaphragm, including a magnet coil disposed in back of the

10

20

diaphragm and located with its core substantially coincidental with the axis of the casing said diaphragm having its peripheral portions secured to the casing.

11. The invention as defined in claim 1 in which the automatic switch means comprises a movably mounted weight constituting the said circuit-closing element and connected in the circuit for the signal means, and comprises a contact engageable by said weight, and in which the said supporting structure comprises releasable means for normally holding the weight in a position separated from the said contact.
